CONVERSION OF HYDROCARBON OILS

John Warren McCaffrey, Chicago, Ill., assignor to
 Universal Oil Products Company, Chicago, Ill.,
 a corporation of Delaware

Application May 23, 1934, Serial No. 727,070
 Renewed September 20, 1935

7 Claims. (Cl. 196—48)

This invention particularly refers to an improved process for the fractional distillation of hydrocarbon oils of relatively wide boiling range accompanied by the selective conversion of relatively low-boiling and relatively high-boiling fractions of the charging stock, together with corresponding low-boiling and high-boiling fractions of the intermediate conversion products of the process.

10 In the present invention the heat required for the topping and cracking operations is derived from a single furnace structure and as a special feature of the invention the arrangement of the heating coils or fluid conduits within the furnace through which the various oils are passed is such that each separate stream of oil is subjected to the heating conditions most suitable for its treatment.

15 In its preferred form the furnace which I employ is of the general type having two separately fired combustion and heating zones with fluid conduits located along the roof and along the floor of each and with a centrally located fluid heating zone supplied with combustion gases from both combustion zones and containing another fluid conduit. It has been found that, in furnaces of this general character, the tube banks adjacent the floor of the combustion zones are subjected to the most severe heating conditions while somewhat 20 milder heating conditions ordinarily prevail in the fluid conduits adjacent the roof of the combustion zones and the mildest heating conditions are obtained about the fluid conduit located in the central or fluid heating zone of the furnace.

25 In the present invention advantage is taken of the normal heating tendencies of this type of furnace by arranging the flow of the various oils to be treated through the different fluid conduits within the furnace in such a manner that each 30 type of oil to be subjected to different conditions of treatment is also subjected to the heating conditions most suitable for that type of treatment to which the particular oil is best suited. This is accomplished by passing the charging stock for the 35 process, which is to be heated to a temperature sufficient to effect its fractional distillation under

40 conditions which preclude any appreciable conversion, through that portion of the fluid conduit within the centrally located fluid heating zone 45 which is heated by contact with partially cooled combustion gases prior to their passage from the furnace, while the relatively high-boiling oils to be subjected to conversion are caused to pass through the fluid conduits located adjacent the 50 floor of the combustion zones wherein they are

subjected to a high rate of heating, so that they may be quickly brought to the desired conversion temperature without being maintained at or near the maximum conversion temperature attained for a sufficient length of time to cause their excessive conversion, and the relatively low-boiling oils to be subjected to conversion are caused to pass first through the fluid conduits located adjacent the roof of the combustion zones, wherein they are heated to a relatively high conversion 5 temperature at a somewhat slower rate of heating than that employed for the relatively high-boiling oils (since less rapid heating is not objectionable for the low-boiling oils), the highly heated 10 low-boiling oils being then maintained at or near the maximum conversion temperature attained 15 for a predetermined time by passing them through that portion of the fluid conduit within the centrally located fluid heating zone which is exposed to the relatively hot combustion gases from the 20 combustion zones of the furnace.

25 These conditions of treatment, namely, rapid and relatively short time heating for high-boiling oils and more prolonged heating to a somewhat higher maximum temperature accompanied by 30 soaking for the low-boiling oils have been found most suitable for the production of high yields of desirable light liquid products, such as motor fuel of high anti-knock value, with a minimum of less desirable products such as coke and gas.

35 The topping coil serves as an economizer to extract the excess residual heat from the combustion gases having passed over the soaking section of the fluid conduit in the centrally located fluid heating zone of the furnace. This residual heat is normally ample to heat the charging stock sufficiently to accomplish its fractional distillation, although, when required, additional heating of the 40 charging stock may be accomplished in any well known manner.

45 The term "soaking," as here used is intended to designate the latter stages of heating of the relatively low-boiling oils wherein they are maintained at or near the maximum conversion temperature previously attained for a predetermined 45 time.

50 It will be apparent from the foregoing that there is a definite cooperative relation in the present invention between the selectivity of the cracking operation, the type of oil undergoing treatment and the heating conditions employed for distillation of the charging stock and for the conversion of each selected fraction of the charging stock and reflux condensate. I am aware that 55 topping and cracking processes and selective

cracking processes have been previously employed. I am also aware that furnaces of the general type described are now in use. The present invention, however, provides a novel and advantageous combination of various features and steps which, although well known in themselves, mutually contribute to produce advantageous results which have not heretofore been obtainable.

The accompanying diagrammatic drawing illustrates an apparatus in which the process may be carried out.

Referring to the drawing, furnace 1 comprises two similar combustion zones 2 and 2' each of which are independently fired by means of firing tunnels such as 3. Combustible fuel, together with a regulated portion or all of the air required for combustion, is supplied to combustion zones 2 and 2' through ducts 4 in the firing tunnels by means of burners 5 of any suitable form, additional air being supplied, as desired, to the combustion zones through ducts 6 and 7 located respectively above and below the firing ducts 4 in each of the tunnels 3. A fluid heating zone 8 is located within the central portion of the furnace and is separated from combustion tunnels 2 and 2' by the respective bridge walls 9 and 9'. The combustion gases from both combustion zones pass over the respective bridge walls and downward through fluid heating zone 8 to flue 10 from which they may pass to a suitable stack, not shown.

A fluid conduit or tube bank 11 comprising, in the case illustrated, a single horizontal row of horizontally disposed tubes 12, connected at their ends in series, is located adjacent the floor of combustion zone 2 and a similar bank 11' is located adjacent the floor of combustion zone 2'. Tube banks 11 and 11' are subjected to heating predominantly by radiation from the materials undergoing combustion in the respective combustion zones 2 and 2' and from the hot refractory walls of the furnace and are exposed to heating conditions normally more severe than those employed in any other tube banks of the furnace.

A fluid conduit or tube bank 13 comprising in the case illustrated, a single horizontal row of horizontally disposed tubes 12 connected at their ends in series, is located adjacent the roof of combustion zone 2 and a similar tube bank 13' is located adjacent the roof of combustion zone 2'. Tube banks 13 and 13' are subjected to heating by radiation from the materials undergoing combustion in the respective combustion zones 2 and 2' and from the hot refractory walls of the furnace and are also subjected to appreciable heating, particularly in the portions above bridge walls 9 and 9', by contact with the hot combustion gases. The average heating conditions in tube banks 13 and 13' are normally somewhat less severe than those to which tube banks 11 and 11' are exposed but are still sufficiently severe that a relatively high average rate of heat input is obtained in the tubes of these banks.

Two separate fluid conduits or tube banks 14 and 15, each comprising a plurality of superimposed horizontal rows of horizontally disposed tubes, connected at their ends in series, are located within fluid heating zone 8 of the furnace. The tube bank 14 is located above tube bank 15 and is therefore exposed to more severe heating conditions since the combustion gases from combustion zones 2 and 2' must pass over the tubes of bank 14 before they reach bank 15. The average heating conditions in each of these banks is,

however, relatively mild as compared to the conditions prevailing about the floor and roof banks although a portion of tube bank 14, particularly the upper two rows of tubes, is subjected to heating by radiation as well as by contact with the hot combustion gases.

Hydrocarbon oil charging stock for the process which may comprise any desired hydrocarbon oil of relatively wide boiling range, specifically including crude petroleum, may be supplied through line 31 and valve 32 to pump 33 by means of which it is fed, in the case here illustrated, through line 34 and valve 35 to tube bank 15, wherein it is subjected to relatively mild heating conditions and brought to a temperature sufficient to effect its substantial vaporization and fractional distillation without being subjected to any appreciable pyrolytic conversion. In the case here illustrated, the charging stock enters the lowermost row of tubes of bank 15, passing in series through adjacent tubes in each row and through adjacent rows of tubes in a general direction countercurrent to the direction of flow of the combustion gases, being discharged from the uppermost row of tubes of bank 15. It is, however, within the scope of the invention, when desired, to pass the oil through the tubes of bank 15 in any other well known manner. The charging stock may, of course, be preheated, when desired, prior to its introduction into heating coil 15, by means of heat recovered from within the system, or in any other well known manner, not illustrated.

The heated charging stock is supplied from tube bank 15 through line 36 and valve 37 into distilling and fractionating column 38 wherein it is separated by vaporization and fractionation into selected relatively low-boiling and high-boiling fractions.

When the charging stock contains any desirable low-boiling fractions such as, for example, motor fuel of satisfactory anti-knock value, this material may be removed as fractionated vapors from the upper portion of column 38 through line 39 and valve 40 to be subjected to condensation and cooling in condenser 41. The resulting distillate, together with any gas produced by the distilling operation may pass through line 42 and valve 43 to collection and separation in receiver 44. Uncondensable gas may be released from the receiver through line 45 and valve 46. The distillate may be withdrawn from receiver 44 through line 47 and valve 48 to storage or to any desired further treatment.

When the charging stock contains no appreciable quantity of low-boiling fractions which it is desirable to recover without conversion, its total low-boiling components to be subjected to conversion including, for example, any or all of the fractions comprising gasoline of poor anti-knock value, naphtha, kerosene, kerosene distillate, light gas oil and the like, may be withdrawn as fractionated vapors from the upper portion of column 38, subjected to condensation in condenser 41 and collected in receiver 44, in the manner previously indicated, to be withdrawn therefrom through line 49 and valve 50 to pump 51 and directed therefrom through line 52, valve 53, line 57 and line 58 to conversion in heating coils 13, 13' and 14, as will be later more fully described. In case low-boiling components of the charging stock, not to be subjected to conversion, are collected in receiver 44, its remaining relatively low-boiling components including, for example, any or all of the materials such as high-

boiling motor fuel fractions, naphtha, kerosene, kerosene distillate, light gas oil, etc., may be separately withdrawn as one or a plurality of side streams from any suitable intermediate point or plurality of points in column 38, for example, through line 54 and valve 55 to pump 56 wherefrom they may be directed through line 57, valve 58 and line 91 to conversion in tube banks 13, 13' and 14, as will be later more fully described.

The remaining components of the charging stock, comprising its relatively high-boiling fractions which remain unvaporized or are condensed in column 38 and collect within the lower portion of this zone, may be withdrawn therefrom through line 59 and valve 60 to pump 61 to be supplied therefrom through line 62, valve 63 and line 86 to conversion in tube banks 11 and 11', as will be later more fully described.

It is, of course, within the scope of the invention to separately recover any desired selected fraction or fractions of the charging stock from column 38, by well known means not here illustrated, particularly in case the charging stock contains valuable intermediate or high-boiling components such as lubricating stock, asphalt, etc. The invention also contemplates preheating of the oils supplied to any heating coil of the furnace, when desired, by well known means not illustrated such as, for example, indirect contact and heat exchange with hot vaporous and/or liquid products of the process.

In the case here illustrated the stream of relatively heavy oil supplied through line 86 to the tubes adjacent the floor of the furnace is split into two streams of substantially equal volume which pass through lines 64 and 64' controlled by the respective valves 65 and 65' into tube banks 11 and 11', respectively, flowing in series through the adjacent tubes of each bank in a general direction concurrent to the direction of firing and being discharged therefrom through the respective lines 66 and 66', the two streams commingling in line 67 and passing through valve 68 in this line into reaction chamber 69. It will be understood, of course, that any other desired flow arrangement may be employed for the relatively heavy oil in heating coils 11 and 11'.

The relatively low-boiling oils supplied through line 91 to heating coils 13 and 13', located adjacent the roof of the furnace, are also, in the particular case here illustrated, split into two streams of substantially equal volume which flow through lines 70 and 70' controlled by the respective valves 71 and 71' into tube banks 13 and 13', respectively, each stream flowing in series through adjacent tubes of the respective banks in a general direction concurrent to the direction of firing and passing from banks 13 and 13', respectively, through lines 72 and 72' into line 73, wherein they commingle, and enter the lowermost row of tubes of bank 14, flowing in series, through adjacent tubes in each row and through adjacent rows of tubes in a general direction countercurrent to the direction of flow of the combustion gases through zone 8, the heated stream of low-boiling oil finally being discharged from the uppermost row of bank 14 through line 14 and valve 75 into reaction chamber 69. The relatively low-boiling oils may, of course, when desired, be passed through tube banks 13, 13' and 14 in any other desired manner, however, tube bank 14 is preferably, in all

cases, utilized as the final heating zone for the low-boiling oils.

A substantial superatmospheric pressure is preferably maintained at the outlet from both the light oil and the heavy oil heating coils and chamber 69 is also preferably maintained at substantial superatmospheric pressure so that conversion of the heated products supplied to this zone, and particularly their vaporous components, may continue therein. Although not indicated in the drawing, chamber 69 is also preferably well insulated in order to conserve heat. In the case here illustrated, both vaporous and liquid conversion products are discharged in commingled state from the lower portion of chamber 69 through line 76 and valve 77 into vaporizing chamber 78. It will be understood that, although not indicated in the drawing, the two streams of hot conversion products instead of entering chamber 69 in commingled state, as indicated in the drawing, may be separately introduced into this zone, each at any desired point and in any well known manner. It is also within the scope of the invention to separately withdraw vaporous and liquid conversion products from chamber 69, although the various well known means whereby this may be accomplished are not illustrated in the drawing. Also, when desired, chamber 78 may be eliminated, in which case residual liquid may be discharged from chamber 69 to cooling and storage or elsewhere, as desired, while the vaporous products separately withdrawn therefrom are subjected to fractionation, or the operating conditions may be so controlled that coke is produced in chamber 69 as the final residual product of the process.

A substantially reduced pressure relative to that employed in chamber 69 is utilized in chamber 78 in order to accomplish further vaporization of the liquid conversion products supplied to this zone. Residual liquid remaining unvaporized in chamber 78 may be withdrawn therefrom through line 103 and valve 104 to cooling and storage or elsewhere, as desired. It is also within the scope of the invention, when desired, to operate chamber 78 for the production of substantially dry coke in this zone, as the final residual product of the process.

In case coking is employed in either chamber 69 or chamber 78 a plurality of such zones may be employed, when desired, although not illustrated, to provide additional space for the deposition of coke and they may be simultaneously operated or, preferably, alternately operated, cleaned and prepared for further operation so that the duration of the operating cycle of the process is not limited by the capacity of the coking zone.

Vaporous products pass, in the case illustrated, from chamber 78 through line 88 and valve 81 to fractionation in fractionator 82, wherein their components boiling above the range of the desired light distillate conversion product of the process are condensed as reflux condensate. The reflux condensate is separated, in the case here illustrated, into selected relatively low-boiling and high-boiling fractions. The high-boiling fractions are withdrawn from the lower portion of fractionator 82 through line 83 and valve 84 to pump 85 wherefrom they are supplied through line 86 and valve 87 to conversion in the heavy oil heating coil, comprising tube banks 11 and 11', together with the high-boiling oil from column 38, supplied to the heating coil as previously described. The low-boiling reflux condensate may be withdrawn from any suitable intermediate

point or plurality of points in fractionator 82, for example through line 88 and valve 89 to pump 90 by means of which this material is supplied through line 91 and valve 92 to further conversion in the light oil heating coil, comprising tube banks 13, 13' and 14, together with selected low-boiling fractions of the charging stock, supplied to this zone as previously described.

Fractionated vapors of the desired end-boiling point are withdrawn, together with uncondensable gas produced by the cracking operation, from the upper portion of fractionator 82 through line 93 and valve 94 and are subjected to condensation and cooling in condenser 95. The resulting distillate and gas passes through line 96 and valve 97 to collection and separation in receiver 98. Uncondensable gas may be released from the receiver through line 99 and valve 100. The distillate may be withdrawn from receiver 98 through line 101 and valve 102 to storage or elsewhere, as desired.

The usual expedients for assisting fractionation of the vapors in column 38 and fractionator 82 may, of course, be employed within the scope 25 of the invention, although not here illustrated. Such expedients may comprise, for example, returning a regulated portion of the distillate from receivers 44 and 98 to column 38 and fractionator 82, respectively.

30 In an apparatus such as illustrated and above described, the preferred range of operating conditions may be approximately as follows: The conversion temperature employed at the outlet from the relatively heavy oil heating coil may range, for example, from 800 to 950° F., or thereabouts, preferably with a substantial superatmospheric pressure, measured at the outlet from the heating coil, of from 100 to 500 pounds, or thereabouts, per square inch. The heating coil to which the relatively low-boiling oil is supplied may utilize an outlet conversion temperature ranging, for example, from 925 to 1050° F., or thereabouts, preferably with a superatmospheric pressure at this point in the system of from 200 to 1,000 pounds, or thereabouts, per square inch. The temperature employed at the outlet from the heavy oil heating coil is preferably within approximately 10°, or thereabouts, of the maximum attained in this zone while the maximum temperature attained in the light oil heating coil is preferably within 30°, or thereabouts, of the outlet conversion temperature from this zone. The temperature to which the charging stock is heated will vary considerably, depending upon its 55 characteristics and the desired degree of separation to which it is subjected as well as upon the pressure conditions employed in the distilling stage of the process. The temperature of the charging stock entering the distilling and fractionating column may range, for example, from 400 to 750° F., or thereabouts. Any desired pressure from substantially atmospheric to 200 pounds, or more, per square inch may be employed at the outlet from the heating coil to 60 which the charging stock is supplied and when superatmospheric pressure is employed in this zone it may be substantially equalized in the distilling and fractionating column but is preferably reduced in this zone to substantially atmospheric. The pressure employed in the reaction chamber may range, for example, from 100 to 500 pounds, or more, per square inch and preferably is substantially reduced in the succeeding vaporizing chamber, when such a zone is employed, to a pressure which may range, for example, from 100

5 pounds, or thereabouts, per square inch down to substantially atmospheric pressure. The pressures employed in the fractionating, condensing and collecting portions of the cracking system may be substantially the same or somewhat lower than the pressure employed in the preceding stage of the process. Under normal operating conditions, with a furnace and a flow there-through such as illustrated and above described, the relatively heavy oils may be subjected to an 10 average rate of heating of the order of 12,500 to 17,500 B. t. u.'s per square foot, per hour, while the average rate of heating to which the relatively low-boiling oils are subjected in the roof banks may range, for example, from 10,000 to 15 15,000 B. t. u.'s per square foot, per hour. The average rate of heating in the soaking section of the light oil heating coil (the tube bank located within the upper portion of the fluid heating zone of the furnace) may range, for example, from 3,000 to 5,000 B. t. u.'s per square foot, per hour and the average rate of heating employed for the charging stock in tube bank located within the lower portion of the fluid heating zone may range, for example, from 2,000 to 3,500 B. t. u.'s 20 per square foot, per hour.

25 As an example of one specific operation of the process of the present invention, a Pennsylvania crude oil of about 45° A. P. I. gravity containing some 37% of gasoline of poor anti-knock value, after being preheated by indirect contact and heat exchange with hot products from within the system, is subjected in a heating coil located within the lower portion of the fluid heating zone of the furnace to a temperature of approximately 550° F., at a superatmospheric pressure of about 100 pounds per square inch and the heated material is introduced into a distilling and fractionating column operated at substantially atmospheric pressure wherein the components of the charging stock boiling up to approximately 500° F., are separated from its higher boiling components. The latter are subjected in the heating coils located adjacent the floor of the two combustion zones of the furnace to 30 an outlet conversion temperature of approximately 950° F., at a superatmospheric pressure of about 300 pounds per square inch and are then introduced into the reaction chamber which is maintained at substantially the same pressure. 35 The low-boiling fractions of the charging stock, including the gasoline and naphtha fractions boiling up to approximately 500° F., are heated in the tube banks of the furnace adjacent the roof of the two combustion zones to a temperature of approximately 1000° F., and are then passed through the tube bank located in the upper portion of the fluid heating zone of the furnace wherein this temperature is substantially maintained, the products being discharged from this zone at a temperature of approximately 980° F., at a superatmospheric pressure of about 800 pounds per square inch into the reaction chamber wherein the pressure is reduced to approximately 300 pounds per square inch. Vaporous 40 and liquid conversion products from the reaction chamber are introduced into alternately operated reduced pressure coking chambers maintained at approximately 30 pounds per square inch superatmospheric pressure and a regulated portion of the heated products from the light oil heating coil are supplied directly to the lower portion of the coking chambers to assist reduction of the residual conversion products to coke. Vaporous products from the coking chambers 45

are subjected to fractionation whereby their insufficiently converted components are condensed as reflux condensate. A selected low-boiling fraction of the reflux condensate, having a boiling range of approximately 385 to 550° F., is subjected to further conversion, together with the low-boiling fractions of the charging stock. The remaining higher boiling fractions of the reflux condensate are returned to further conversion, together with the high-boiling fractions of the charging stock. This operation will yield, per barrel of charging stock, about 68% of motor fuel having an anti-knock value equivalent to an octane number of approximately 72 and about 40 pounds of substantially dry coke, the remainder being chargeable principally to uncondensable gas.

I claim as my invention:

1. In a process for the fractional distillation of hydrocarbon oil accompanied by the pyrolytic conversion of selected fractions thereof under independently controlled temperature and pressure conditions in a heating zone employing a heating coil of the type having two independently fired combustion zones with a fluid conduit located adjacent the roof and floor of each and with a centrally located fluid heating zone containing fluid conduits heated by combustion gases from both combustion zones, the improvement which comprises passing hydrocarbon oil charging stock for the process through the fluid conduit located in that portion of the fluid heating zone exposed to the mildest heating conditions therein, whereby to heat the oil to a temperature sufficient to effect its fractional distillation, passing selected high-boiling fractions of the charging stock through the fluid conduits located adjacent the floor of each combustion zone whereby to rapidly heat the same to the desired conversion temperature, without maintaining the same near the maximum conversion temperature attained for a sufficient time to permit excessive conversion thereof, and passing selected low-boiling fractions of the charging stock first through the fluid conduits located adjacent the roof of each combustion zone, whereby to heat the same to a high conversion temperature, and then passing the stream of low-boiling highly heated oil through the fluid conduit located in that portion of the fluid heating zone exposed to the most severe heating conditions therein, whereby to maintain the same near the maximum conversion temperature attained for a predetermined time.
2. In a process for the fractional distillation of hydrocarbon oil accompanied by the pyrolytic conversion of selected fractions thereof under independently controlled temperature and pressure conditions in a heating zone employing a heating coil of the type having two independently fired combustion zones with a fluid conduit located adjacent the roof and floor of each and with a centrally located fluid heating zone also containing fluid conduits heated by combustion gases from both combustion zones, the improvement which comprises passing hydrocarbon oil charging stock for the process through the fluid conduit located in that portion of the fluid heating zone exposed to the mildest heating conditions therein, whereby to heat the oil to a temperature sufficient to effect its fractional distillation, passing selected high-boiling fractions of the charging stock through the fluid conduits located adjacent the floor of each combustion zone, whereby to rapidly heat the same to the desired conversion temperature without maintaining the same near the maximum conversion temperature attained for a sufficient time to permit excessive conversion thereof, passing selected low-boiling fractions of the charging stock first through the fluid conduit located adjacent the roof of each combustion zone, whereby to heat the same to a high conversion temperature, and then passing the stream of low-boiling highly heated oil through the fluid conduit located in that portion of the fluid heating zone exposed to the most severe heating conditions therein, whereby to maintain the same near the maximum conversion temperature attained for a predetermined time, separating the resulting vaporous and residual conversion products of the process, subjecting the vapors to fractionation whereby their insufficiently converted components are condensed as reflux condensate, subjecting fractionated vapors of the desired end-boiling point to condensation, recovering the resulting distillate, separating the reflux condensate into selected relatively low-boiling and high-boiling fractions, returning the high-boiling fractions to further conversion, together with said high-boiling fractions of the charging stock and returning the low-boiling fractions of the reflux condensate to further conversion, together with said low-boiling fractions of the charging stock.
3. In the heating of hydrocarbon oils in furnaces having a pair of independently fired combustion zones and a convection zone receiving combustion gases from both combustion zones, and each of the combustion zones having floor tubes and roof tubes; the method which comprises heating charging oil for the process to distillation temperature in the convection zone substantially by convection from the combustion gases and then subjecting the same to fractional distillation, passing selected high-boiling fractions of the charging oil through the floor tubes of each combustion zone and heating the same therein to cracking temperature substantially by radiation under a relatively high rate of heating, and passing selected low-boiling fractions of the charging oil through the roof tubes of each combustion zone and heating the same therein to cracking temperature substantially by radiation under a lower rate of heating than the high-boiling fractions in the floor tubes.
4. The method as defined in claim 3 further characterized in that said combustion gases, prior to their use in heating the charging oil, are passed over soaking tubes disposed in the convection zone, said low-boiling fractions being passed through such soaking tubes after the heating thereof in said roof tubes whereby to maintain the same at cracking temperature for a predetermined time.
5. In the heating of hydrocarbon oils in furnaces having a pair of independently fired combustion zones and a convection zone receiving combustion gases from both combustion zones, and each of the combustion zones having floor tubes and roof tubes; the method which comprises heating charging oil for the process to distillation temperature in the convection zone substantially by convection from the combustion gases and then subjecting the same to fractional distillation to form a relatively heavy fraction and a lighter fraction, dividing each of said fractions into two substantially equal streams, passing each stream of the heavy fraction through the floor tubes of one of the combustion zones and heating the same therein to cracking temperature.

conversion temperature without maintaining the same near the maximum conversion temperature attained for a sufficient time to permit excessive conversion thereof, passing selected low-boiling fractions of the charging stock first through the fluid conduits located adjacent the roof of each combustion zone, whereby to heat the same to a high conversion temperature, and then passing the stream of low-boiling highly heated oil through the fluid conduit located in that portion of the fluid heating zone exposed to the most severe heating conditions therein, whereby to maintain the same near the maximum conversion temperature attained for a predetermined time, separating the resulting vaporous and residual conversion products of the process, subjecting the vapors to fractionation whereby their insufficiently converted components are condensed as reflux condensate, subjecting fractionated vapors of the desired end-boiling point to condensation, recovering the resulting distillate, separating the reflux condensate into selected relatively low-boiling and high-boiling fractions, returning the high-boiling fractions to further conversion, together with said high-boiling fractions of the charging stock and returning the low-boiling fractions of the reflux condensate to further conversion, together with said low-boiling fractions of the charging stock.

3. In the heating of hydrocarbon oils in furnaces having a pair of independently fired combustion zones and a convection zone receiving combustion gases from both combustion zones, and each of the combustion zones having floor tubes and roof tubes; the method which comprises heating charging oil for the process to distillation temperature in the convection zone substantially by convection from the combustion gases and then subjecting the same to fractional distillation, passing selected high-boiling fractions of the charging oil through the floor tubes of each combustion zone and heating the same therein to cracking temperature substantially by radiation under a relatively high rate of heating, and passing selected low-boiling fractions of the charging oil through the roof tubes of each combustion zone and heating the same therein to cracking temperature substantially by radiation under a lower rate of heating than the high-boiling fractions in the floor tubes.

4. The method as defined in claim 3 further characterized in that said combustion gases, prior to their use in heating the charging oil, are passed over soaking tubes disposed in the convection zone, said low-boiling fractions being passed through such soaking tubes after the heating thereof in said roof tubes whereby to maintain the same at cracking temperature for a predetermined time.

5. In the heating of hydrocarbon oils in furnaces having a pair of independently fired combustion zones and a convection zone receiving combustion gases from both combustion zones, and each of the combustion zones having floor tubes and roof tubes; the method which comprises heating charging oil for the process to distillation temperature in the convection zone substantially by convection from the combustion gases and then subjecting the same to fractional distillation to form a relatively heavy fraction and a lighter fraction, dividing each of said fractions into two substantially equal streams, passing each stream of the heavy fraction through the floor tubes of one of the combustion zones and heating the same therein to cracking temperature.

ture substantially by radiation under a relatively high rate of heating, and passing each stream of the lighter fraction through the roof tubes of one of the combustion zones and heating the same therein to cracking temperature substantially by radiation under a lower rate of heating than the streams of the heavy fraction in the floor tubes.

6. In the heating of hydrocarbon oils in furnaces having a pair of independently fired combustion zones and a convection zone receiving combustion gases from both combustion zones, and each of the combustion zones having floor tubes and roof tubes; the method which comprises heating charging oil for the process to distillation temperature in the convection zone substantially by convection from the combustion gases and then subjecting the same to fractional distillation to form a relatively heavy fraction and a lighter fraction, dividing each of said fractions into two substantially equal streams, passing each stream of the heavy fraction through the floor tubes of one of the combustion zones and heating the same therein to cracking temperature substantially by radiation under a relatively high rate of heating, and passing each stream of the lighter fraction through the roof tubes of one of the combustion zones and heating the same therein to cracking temperature substantially by radiation under a lower rate of

heating than the streams of the heavy fraction in the floor tubes, then combining the streams of the lighter fraction and passing the mixture thereof in indirect heat exchange with the combustion gases in the convection zone prior to the use of the gases in the heating of the charging oil, whereby to maintain the lighter fraction at cracking temperature for a predetermined time.

7. In the heating of hydrocarbon oils in furnaces having a pair of independently fired combustion zones and a convection zone receiving combustion gases from both combustion zones; the method which comprises heating charging oil for the process to distillation temperature in the convection zone substantially by convection 15 from the combustion gases and then subjecting the same to fractional distillation, passing selected high-boiling fractions of the charging oil through a portion of each combustion zone wherein a relatively high rate of heat input prevails and heating the same therein to cracking temperature substantially by radiation under the high rate of heat input, and passing selected low-boiling fractions of the charging oil through another portion of each combustion zone wherein 20 a lower rate of heat input prevails and therein heating the same substantially by radiation to cracking temperature under a lower rate of heat input than the high-boiling fractions.

JOHN WARREN McCAFFREY. 30
